UNITED STATES PATENT OFFICE.

FRANK B. DAVIDSON, OF MARSEILLES, ILLINOIS, ASSIGNOR TO HOWE AND DAVIDSON COMPANY, OF MARSEILLES, ILLINOIS, A CORPORATION OF NEW JERSEY.

PARTITION MEMBER FOR CONTAINERS.

1,307,621.

Specification of Letters Patent. Patented June 24, 1919.

Application filed September 7, 1916. Serial No. 118,793.

To all whom it may concern:

Be it known that I, FRANK B. DAVIDSON, a citizen of the United States, residing at Marseilles, in the county of La Salle and 5 State of Illinois, have invented new and useful Improvements in Partition Members for Containers, of which the following is a specification.

This invention relates to improvements in 10 partition members or separators of that kind ordinarily employed in the packing of goods of a fragile character, in containers, cartons, and shipping cases, and more in particular to the manner in which the several parts, 15 comprising a partition member or separator, are formed and assembled to provide the completed structure.

Partition members or separators of the character referred to are commonly constructed of sheet material such as cardboard, fiber-board, or the like, and consist 20 of a plurality of strips, arranged in parallel rows, which intersect each other at right angles and are connected together by means 25 of interlocking notches formed in the margins of the strips at the several points of intersection, thereby forming a rectangular, 30 crate-like structure, having a plurality of smaller rectangular compartments or units, in which one or more of the articles or goods are placed.

In the manufacture of devices of this character, the locking notches are ordinarily 35 cut from the material of the strips by means of suitable cutting machinery, said notches being substantially of the same width as the thickness of material of the strips, in order that a snug or close fit can be secured between the notches and thus obtain a desirable 40 degree of rigidity and stability in the structure. It has been found, however, that the cutting or forming of notches, or narrow marginal slots, is an exceedingly difficult and laborious operation, for the reason that 45 the operation of cutting the notches involves the severing and removing from the strips of an exceedingly narrow portion of the material or "trim," as it is called, to provide the marginal slots of the desired width. Because 50 of the narrow width of the "trim" to be removed, considerable difficulty is experienced in the cutting operation, for the

reason that the "trim" has not sufficient body to permit its being severed from the material of the strip in a clean and uniform 55 manner. Furthermore, the "trim" is manifestly difficult of removal from the narrow form of notch, on account of the close proximity of the margins and the rectangular shape thereof, with the result that the "trim" 60 tends to adhere or remain lodged within the notch, thus necessitating the expenditure of considerable time and labor in properly freeing the notches of the "trim" after the same has been cut. The difficulties experienced in 65 the cutting operation are greatly increased when a number of strips are operated on simultaneously, as is the common practice in the manufacture of these devices. Manifestly, therefore, while the narrow form of 70 slot or notch is desirable to produce a stable crate layer structure, the difficulty in forming the slots has led to the substitution, for the narrow slot with parallel edges, of a different form or shape of slot, namely, a substantially V-shaped notch. From the standpoint of manufacture, the V-shaped notch is 75 much superior to the narrow form of notch, for the reason that notches thus formed are considerably greater in width, hence can 80 be cut with greater ease and in a clean and workmanlike manner. Furthermore, the shape and increased width and size of the "trim" permits the same to be removed with little difficulty, inasmuch as the "trim" is 85 more accessible, and the tendency to become lodged in the notch is practically eliminated.

A V-shaped notch, however, is obviously not, in itself, calculated to provide a rigidly constructed crate structure, for the reason 90 that such a slot is incapable of contacting with or bearing against both sides or surfaces of a strip inserted therein, so as to maintain the same in upright position, as is true in the case of the narrow form of notch, 95 but it has been found that this apparent disadvantage of the V-shaped notch can be overcome, by employing a method of arranging the notches in the strips and of arranging or assembling the several strips, whereby 100 the same degree of rigidity and stability can be secured in the completely assembled partition member, and at the same time securing the advantages hereinbefore set forth in

connection with the manufacture of the strips.

It is to these features that the present invention relates, the same being hereinafter described in detail and illustrated in the accompanying drawings, in which:

Figure 1 is a view in perspective of a complete partition member, made and assembled in accordance with my invention; and

10 Fig. 2 is a view in perspective of the strips disassembled, but arranged in the relative positions occupied when assembled.

Referring now in detail to the partition member or separator embodying my invention, the same comprises a plurality of strips or crate members, which are formed from sheet material such as card- or fiber-board, as before stated. These strips are preferably of the same width, although they 15 may vary in length, depending on the size or particular shape of the partition member desired. The method of forming the locking notches is quite the same for all the strips, therefore a description of one strip in 20 this regard will suffice for all. Considering, therefore, either of the lowermost strips of Fig. 2, the same are provided along one of their longitudinal margins, namely, the upper margin, with a plurality of notches 10 preferably spaced apart, throughout the 25 length of the strips, in equidistant relation. These notches are substantially V-shaped, although, to describe their shape more exactly, they consist of or are formed by means 30 of cuts or edges 11 and 12 inclined at angles to each other, one of the edges, 11, extending perpendicular or at right angles to the upper longitudinal margin of the strip and inwardly from said margin a distance substantially 35 equal to one-half the width of the strip, the other edge or cut, 12, being inclined at an angle of approximately thirty degrees (30°) to the perpendicular edge 11 and joining the inner end of the same, to 40 form a sharp point or apex of the notch. In addition to the edges already described, each notch is preferably provided with a short inclined edge 13 at the entrance thereof and adjacent to the outer end of the perpendicular edge 11, said short edge being inclined at 45 approximately an angle of thirty degrees (30°) to the perpendicular edge 11 and in the opposite direction from the inclined edge 12. The presence of this short inclined edge 50 eliminates the sharp or right-angled corner that would otherwise be present at one side of the entrance of the notch, thereby facilitating the entrance of a strip therein.

Referring now to the notches of each strip, it is to be pointed out that all of the notches formed along the same margin of a strip bear the same relation to one another, that is, the several edges 11, 12, and 13 of all of the notches are parallel with each other and otherwise occupy corresponding

positions. The pertinency of this observation will be appreciated in connection with what follows.

Although all of the strips may be said to be similar, as regards their formation, it is 70 preferred, for the sake of clearness of description, to divide the several strips into two or more series, each embracing a plurality of parallel strips arranged transversely or at right angles to the other series (or tier immediately above or below, as they are shown in Fig. 2). Series A, therefore, comprises two strips 14 and 15, spaced apart in parallel relation and in upright position, the same being 75 identical in formation but reversed as regards the relative position of the notches 10 of each strip; that is to say, the position of a notch 10 of one strip is in the reverse position of the corresponding notch of the other strip, thus the perpendicular edges 11, 11, as 80 well as the inclined edges 12, 12 of corresponding notches, are located on opposite sides of a transverse plane passing through the apex of each notch. This relationship or disposition of the strips is accomplished 85 by merely reversing two identically formed strips longitudinally.

The second series or tier B, as illustrated, 90 consists of four strips arranged in parallel and spaced-apart relation and identical in 95 formation, but differing from the strips of series A in the following particular. These strips are provided along both of their longitudinal margins with notches 16 and 17 spaced apart at equal distances, the notches 100 16 being located along the lower margin and adjacent the ends of the strip, and the notches 17 located along the upper margin and intermediate the notches 16, 16. As regards the relative positions of the notches, 105 it is to be noted that the perpendicular edges 18 and inclined edges 19 of all the notches are on corresponding sides, but that the inclined edges 19 of the notches 16 and 17 are necessarily not parallel, inasmuch as they 110 are located on opposite margins of the strips.

The strips of series B may be further divided into pairs, each consisting of strips 20 and 21, the strips of each pair being arranged in corresponding relation as regards 115 the disposition of the notches thereof, but the several strips 20 and 21 are alternately arranged as regards the disposition of the notches of each alternate strip. Referring to the relation of the notches 16 and 17 of the alternately arranged pairs of strips 20 and 21, it is to be noted that the corresponding notches 16 and 17 of each strip are in transverse alinement, but that they are 120 alternately reversed, that is, the perpendicular and inclined edges 18 and 19 of the notches 16 and 17, respectively, are alternately disposed on opposite sides of a transverse plane passing through the apex of each 125 of the lined notches. This relationship ex- 130

ists or is followed throughout each group or set of transversely alined notches, and is accomplished by merely reversing longitudinally each alternate strip 20 and 21, said 5 strips being otherwise identical in form.

Series C comprises two identically formed, parallel strips 22 and 23 having the same formation as the strips 14 and 15 of series A, although so arranged that the notches 24 10 thereof are located along the lower margin of the strips and face downwardly. These strips are also arranged so that the corresponding or transversely alined notches are disposed in reversed relation, in the same 15 manner as described in connection with said strips 14 and 15, namely, the perpendicular edges 25 and inclined edges 26 are located on opposite sides of a vertical plane passing through the apex of each notch.

20 With the several strips formed and arranged as hereinbefore described, the manner in which the same are assembled to form the completed partition member will be understood from the following. Referring 25 to Fig. 2, let it be assumed that the strips 14 and 15 of series A are first supported in the positions shown, and that the strips 20 and 21 of series B are allowed to drop or be moved downwardly, following the dotted 30 lines. In this manner, the notches 16, 16 at the end of the strips 20, 21 will enter and engage the notches 10, 10, the strips coming to rest with the upper and lower margins thereof lying in substantially the same horizontal 35 planes, as shown in Fig. 1. Considering now more in detail the nature of the locking engagement between the strips of series A and a single strip 20 of series B (for instance, the left-hand strip 20 in Figs. 1 and 2), it will 40 be noted that the perpendicular edges 11 of the notches 10, 10 of strips 14 and 15 contact with the strip 20 at the opposite ends thereof, and likewise on opposite sides or faces of the strip, thus providing lateral support 45 on both sides of said strip 20, serving to maintain the same in a vertical and upright position. With a single strip 20 of series B in position, it is clear that the strips 14 and 15 of series A are not stable, inasmuch as the 50 V-shape of the notches permits the latter to tilt to the left, or toward the inclined edges of the notches 16 of the strip 20. But upon the addition of the next strip 21, a rigid structure is formed, for the reason that the 55 perpendicular edges 18 of the notches 16 thereof contact with the opposite surface of the strips 14 and 15 from that in contact with the perpendicular edges 18 of the strip 20, hence the strips 14 and 15 are now restrained 60 from tilting toward the left or inclined edge of notch 16 of strip 20, and thus are held in upright position. And so, upon the addition of the other strips 20 and 21, the strips 14 and 15 are further supported by 65 perpendicular edges on opposite sides there-

of, which act to support the strips 14, 15 in upright position, the same in turn supporting the strips 20 and 21 in like manner, by the alternate arrangement of the corresponding notches 10, whereby a perpendicular 70 edge contacts with opposite surfaces at the ends of each of said strips 20 and 21.

As thus far described the partition member consists of the strips of series A and B, and is itself quite an independently rigid 75 structure. The addition of the strips 22 and 23 of series C, however, makes an even more rigid structure, as will presently be seen. Now assuming that the strips 22 and 23 are lowered along the dotted lines of Fig. 2 until 80 they engage the strips of series B, that is, until the notches 24 of said strips 22 and 23 enter and are engaged by corresponding notches 17 of the strips 20 and 21. By the addition of strips 22 and 23 two distinct 85 results are forthcoming. In the first place, the notches 24 of the strips 22 and 23 being reversed, the perpendicular edges of each two corresponding notches will engage opposite sides of each strip 20 and 21, thus serving to 90 maintain said strips 20 and 21 in parallel and upright position. In the second place, the strips 20 and 21 perform a reciprocal function with respect to the strips 22 and 23, in that the transversely alined notches 17, 17 95 being alternately reversed, with respect to the disposition of the perpendicular edges thereof, the said strips 22 and 23 are supported and maintained in upright position and incapable of lateral or tilting movement. 100

Considering, generally, the relation which exists between the strips 14 and 15 of series A and strips 22 and 23 of series C, it is to be noted that these several parallel strips when assembled are not only arranged in parallel 105 relation, but that the corresponding transversely alined notches of said strips are disposed in alternately reversed relation, thereby positioning a perpendicular edge alternately on opposite sides of each strip of series B, in exactly the same manner that the notches of series B are alternately reversed to support each strip of series A and C, as hereinbefore described. 110

To summarize briefly, what appears to be 115 the paramount result, accomplished by the structure and arrangement of the several strips as herein described, is the production of a crate or separator made entirely of strips having V-shaped notches, which interlock at the points of intersection, and each and every strip supported in upright position by at least two perpendicular edges of the notches in contact therewith throughout its length and alternately disposed on opposite sides thereof. It is by reason of the particular arrangement of the several strips that it is possible to construct a partition member provided with the superior V-shaped form of notch, yet having substan- 120 125 130

tially the same degree of rigidity as is obtained by the use of the usual narrow type of notch.

As already suggested, the advantages forthcoming from this arrangement or construction of crate are primarily associated with the manufacture and production of such devices, and more particularly with a method of cutting or forming the strips or units of a complete crate whereby a material reduction in the cost of production is obtained. This result is secured, first, by utilizing a form of notch which is far superior and more practical, from the standpoint of manufacture, to the ordinary narrow, parallel edged form of notch, and, secondly, by employing a method of assembling the strips, so that the apparent instability and lack of rigidity, that would seem to follow from the use of the V-shaped notch, is successfully avoided. It follows, therefore, that the crate embodying the features of the invention takes to itself all the advantages of stability and rigidity that must necessarily accompany the use of narrow form of notch, at the same time eliminating the disadvantages which accompany the cutting or forming of said narrow form of notch.

Obviously the simplest form of crate that can be constructed, embodying the arrangement of the strips and notches as herein described, is one comprising two transversely arranged series of at least two strips each. This simple form of crate can clearly be elaborated, by multiplying the number of series or the number of strips in each series, without departing from the principle herein disclosed. For this reason it is not intended to limit the scope of the invention to the particular form of device herein described and illustrated, except in so far as expressly limited by the appended claims.

I claim as my invention:

1. A partition member for containers, embracing a set of two flat partition strips having V-shaped notches opening through one of the longitudinal edges of said strips, a second set of two flat partition strips extending between the strips of said first set and having V-shaped notches opening through one of the longitudinal edges of said strips and adapted to have interlocking engagement with the notches in the strips of said first set, each notch in each strip having one edge perpendicular to the edge of the strip through which said notch opens, and one strip of each set being arranged in a position reverse to the other strip of the same set so that the perpendicular edges of the notches of the strips in each set face in

opposite directions and engage the intersecting strips of the other set on opposite sides thereof.

2. A partition member for containers, embracing a set of flat partition strips, a second set of flat partition strips arranged transverse to the strips of said first set, and a third set of flat partition strips arranged transverse to the strips of said second set, each of said strips having V-shaped notches opening through one of the longitudinal edges thereof and adapted to have interlocking engagement with the notches of the strips arranged transverse to said strips, each notch having one edge perpendicular to the edge of the strip through which said notch opens, and one strip of each set being arranged in a position reverse to another strip of the same set so that the perpendicular edges of the notches of said strips face in opposite directions and engage the strips arranged transverse thereto on opposite sides thereof.

3. A partition member for containers, embracing a set of partition strips having V-shaped notches opening upward through the upper longitudinal edges of said strips, a second set of partition strips arranged transverse to the strips of said first set and having V-shaped notches opening downward through the lower longitudinal edges of said strips and adapted to have interlocking engagement with the notches of the strips of said first set; the strips of said second set having additional V-shaped notches opening upward through the upper longitudinal edges of said strips, a third set of strips arranged transverse to the strips of said second set and having V-shaped notches opening downward through the lower longitudinal edges of said strips and adapted to have interlocking engagement with the upwardly opening notches in the strips of said second set, each notch in each strip having one edge arranged perpendicular to the edge of the strip through which the notch opens, and at least one strip of each set being arranged in a position reverse to that of another strip in the same set so that the perpendicular edges of the notches in said strips face in opposite directions and engage the strips arranged transverse thereto on opposite sides thereof.

In testimony that I claim the foregoing as my invention, I affix my signature in the presence of two witnesses, this 18th day of August, A. D. 1916.

FRANK B. DAVIDSON.
